UNITED STATES PATENT OFFICE.

CHARLES E. SANDSTROM, OF CHICAGO, ILLINOIS.

DESIGN FOR A MOLDING.

SPECIFICATION forming part of Design No. 28,085, dated December 21, 1897.

Application filed September 28, 1896. Serial No. 607,265. Term of patent 14 years.

To all whom it may concern:

Be it known that I, CHARLES E. SANDSTROM, a citizen of the United States, residing at Chicago, in the county of Cook and State of Illinois, have invented and produced 5 a new and original Design for Moldings, of which the following is a specification, reference being had to the accompanying drawings.

In the drawing which forms a part of this 10 case I have shown in perspective a section of a molding illustrating my design.

By reference to said drawing it will be seen 15 that my new design consists of a molding with its opposite sides of such configuration as to present a curved or scroll form in cross-section, the ornamentation or configuration on either side of an imaginary line drawn through the longest diameter of the molding being in reverse position relative to each 20 other.

Referring to the drawing by letter, it will be seen that my design, as illustrated, consists 25 of the molding, scroll-shaped or curved in cross-section, with two ornamental faces lying

in reversed position relative to each other on 25 either side of the imaginary line xx . These faces, as shown, have the principal or main bead-like portions $A A'$ and the body portions $B B'$ curving to the lip-like terminations $b b'$. The ornamental faces just described lie in 30 reverse order with respect to one another on either side of the dotted line xx —i. e., the bead A is approximately opposite the body portion B' and its rib-like ornamentation b' formed on the other face of the molding, 35 while the bead A' is similarly positioned with respect to the body portion B and rib-like portion b .

Having thus set forth the distinguishing 40 features of my new and original design, I claim—

The design for a molding herein shown and described.

CHARLES E. SANDSTROM.
